[57] **ABSTRACT**

A parking system and method adapted to complete automation is provided. Vehicles are stored on in-

dividual storage platforms occupying parking spaces arranged by parallel rows and in defined areas on the floors of a multi-floor building. Certain rows for vehicle movement are designated as aisles and the spaces cross-wise make up what are designated as bays. The platforms are mechanically moveable laterally and a selected space is left unfilled in each bay which enables any selected service aisle to be cleared by shifting storage platforms as required and makes each storage platform accessible. Each area on each floor has its own aisle clearing mechanism. During parking and discharge operations which may be completely automatic the platforms are shifted as required and the vehicle is mechanically moved down a selected cleared service aisle from or to an elevator which services that particular aisle on each floor. Plural independent elevators are employed. Each elevator is adapted to mount an elevator platform and at the ground or base level each elevator platform is detachable from the elevator and is mechanically moveable laterally independently of the elevator itself. A particular elevator platform is thereby enabled to either mate with an elevator which mates with a particular entranceway or with an elevator which mates with a particular service aisle. Alternatively, the elevator platform may be moved to a base level position which mates with no elevator. Each elevator after receiving an incoming vehicle can rotate 180° for discharge orientation of the vehicle and mechanical means are provided for moving the vehicle on and off the elevator platforms.

METHOD AND APPARATUS FOR LOCKING VEHICLES ON MOBILE PLATFORMS

BACKGROUND OF THE INVENTION

1. Field of the Invention

The invention relates to methods of parking or warehousing vehicles or the like and to the systems, machines, building structures and handling apparatus associated with the same. The invention is especially concerned with mechanical and semi-automatic or automatic parking apparatus or machines.

2. Description of the Prior Art

The prior art teaches various types of multi-level parking garages but unlike the present invention. Examples are to be found in U.S. Pat. Nos. 1,829,023, 2,602,557, 2,605,911, 2,650,728, 2,762,515, 2,930,496 and 2,994,445. A relatively complete and up-to-date survey of parking structures is also to be found in the book "Metropolitan Parking Structures," by Dietrich Klose and published by Frederick A. Praeger, Publisher, Inc., New York (1965).

The cited prior art teaches employment of vertically, laterally and rotatably moveable elevators and storing the vehicles on laterally moveable platforms. The feasibility of handling an unattended vehicle entirely mechanically has also been recognized. However, the fact that automated prior art parking garages have not been proven successful is attested to by the fact that extremely large and highly mechanized systems have been abandoned in recent years. Therefore, the prior art clearly reveals a need for some new and more practical machinery, system and method of handling vehicles mechanically during garage operations.

For comparison with the present invention one prominent type of "pigeon hole" system in the prior art is based on using a single elevator that can move both vertically and laterally in the garage. Only one vehicle can be parked or retrieved at any one time and the vehicles are stored in stalls which are required to be immediately adjacent the elevator. Parking capacity is thus limited to the depth of one vehicle space on each side of the elevators and a shaft running across the building is required. Furthermore, this and other forms of prior art systems have not succeeded in eliminating the need for operators and the accompanying needs for fire escapes, stairs, elevator gates, emergency lights etc.

While it has been known to store vehicles on laterally moveable platforms and to service any aisle of the floor by a single elevator that is located at one end of the floor and that can shift laterally to mate with any aisle, it has not been known to arrange each floor in plural aisles and by areas, to service only selected aisles with independently operating elevators to store each vehicle on a laterally moveable platform, and to provide independent means in each area for clearing an aisle by shifting the platforms and to handle the vehicle mechanically both when moving along the floor aisles and when at the ground or base level entranceway. It has furthermore not been known to provide elevator platforms which at the ground or base level can shift laterally to mate with the lifting portion of any of several elevators, or to mate with any of several entranceways or to move to positions designed to temporarily get one vehicle out of the way of another vehicle.

In other aspects of the prior art because of limited elevator and handling capacity the traffic is normally

directed into a single or at least at the most two streams when directed into a mechanical handling system which of course entails delays particularly during peak periods. The system of the present invention on the other hand because of a simplified but higher elevator and parking capacity lends itself to use of two, three, four or more entranceways and equal numbers of independently operable and mating elevators.

Another related aspect of the prior art concerns the fact that no standard parking machine has yet been devised that satisfactorily adapts itself to other than some uniform rectangular lot shape. That is, available real property sites for parking garages frequently have offsets in the property lines or the lot may have a narrow entrance area and a wide rear area available for parking structure. In any event irregular or odd lot shapes have generally called for custom made parking garage constructions and there has been no way of using a standard set of parking machine components and adapting these to whatever lot shape is available. On the other hand applicant's components are directed to regular as well as irregular lot shapes.

SUMMARY OF INVENTION

GENERAL BACKGROUND

The invention is directed both to a method as well as a system or apparatus for storage of uniform and non-uniform size vehicles or the like. The apparatus may also be properly thought of as being a "machine" for mechanical storage and retrieval. The method and mechanical handling equipment of the invention lends itself to single as well as multi-level structures, to both existing and new constructions, to interior as well as corner lots, to odd as well as regular shaped lots, and to buildings having below ground as well as those not having below ground levels. The Invention will be described however as applied to a structure specifically intended for use in carrying out the system and method of the invention. In particular, an ideal application as presently envisioned is that of parking on ground and above ground levels and in a three story building built on an interior rectangular lot and designed to accommodate 150-175 cars. The invention readily lends itself to being fully automatic in this application. Such type parking facilities are widely needed particularly to give ready access to downtown stores and the like and the required relatively narrow interior lots are available and are not otherwise being efficiently utilized in many of our major cities.

For purposes of summarizing the invention the particular embodiment disclosed will be used as a reference and later description will show other variations suited to the invention. In the selected embodiment, three laterally spaced entranceways are provided and it is here that the owner parks his car on a receiving platform with the left front wheel in a depression and with the wheels free to turn, i.e. "free wheeled" and it is where the owner picks up his car. The terms "parking" and "unparking" will be used in reference to such operations. The owner is given a token or other suitable device with a number corresponding to the storage platform on which the vehicle is to be stored and from this point the vehicle may be handled entirely automatically and mechanically and a fully automatic

system will be assumed for purpose of summarizing the invention though the system may be readily designed so that each operational step is controlled by an attendant at an entranceway control station.

With automatic operation, the attendant at ground level closes a selected master switch which is on a master control board and which initiates a series of operations which may be performed in sequence or to some extent simultaneously depending on the nature of the circuitry employed. To illustrate, it has been mentioned that each vehicle is stored on a laterally moveable storage platform and that access to a particular storage platform is gained by mechanically shifting whatever storage platforms are required to place the particular storage platform in an aisle serviced by an elevator and to clear such service aisle of all storage platforms required to provide a clear aisle path between the arrival position of the mating elevator and the particular storage platform. Furthermore, it has been mentioned that the vehicle is mechanically moved down the service aisle between its storage platform and the corresponding elevator and apparatus used for aisle movement is referred to as an "aisle mover". There is preferably a master switch for each storage platform and when a particular vehicle is properly parked at the entranceway the closing of the master switch plus a "park" or "unpark" switch initiates both a mechanical moving mechanism, referred to as the "entrance mover", which moves the vehicle forward into the machine and onto an elevator platform and also initiates the required aisle clearing and aisle mover operations on the particular floor on which the vehicle is to be parked. That is, it is desirable that the control system be programmed so that all empty and filled spaces are always known and so that when an arriving vehicle is to be parked or unparked the pushing of a single master switch corresponding to the storage platform on which the vehicle is to be or is stored plus a park or unpark switch will automatically initiate whatever operations are required to park or unpark the vehicle.

Since program controls of the kind required by the invention are readily available no detailed reference or claim is made to specific controls, per se. The description and this summary are limited to an indication of where the prime control switches are located in the system and from this those skilled in the art will readily visualize the specific form of control required. Thus, throughout the description various timing sequences will be described and various control switches, though not shown, will be mentioned as controlling operation of the various devices of the invention. Reference may also be made to the cited prior patents for circuitry of the same general type and which may be adapted by those skilled in the art. In considering circuitry for the invention it should also be understood that the system and method of the invention lend themselves to either a fully automated, a semi-automated, or non automation approach. The specific circuitry employed will thus be dictated by the degree of automation employed in a specific application. In a fully automated system the garage attendant will push only two buttons corresponding to a storage platform and a park or unpark requirement and which will initiate a time sequence of events. For example, the selection of a specific storage

platform may cause an aisle accessible to such platform to be cleared on the particular floor. At the ground or base level, the vehicle may in the meantime be caused to be mechanically moved on to an elevator platform, and once upon the elevator platform may then be caused to be rotated 180 degrees by the elevator, after rotation may be caused to be positioned to the level of the selected floor, when at the selected floor may be engaged by the respective aisle mover, later described, moved onto the respective selected storage platform and released by the aisle mover and finally laterally shifted, if required, while on the storage platform. As will be more fully appreciated after reading the description to follow, the foresaid events are not required to take place in any particular order and thus the control system adopted for the invention may vary substantially in form. Furthermore, in a semi-automated system it will be appreciated that each of the mentioned events can be effected by actuation of a separate control switch in a step by step sequence. In general, retrieval of a vehicle, from a control circuitry viewpoint, requires essentially the same type of control circuitry but also offers the same variety of circuitry possibilities in carrying out the invention.

ENTRANCE MOVER

The referred to entrance mover has as its function during parking the moving of the vehicle from the entranceway receiving platform to a mating elevator platform and during unparking the moving of the vehicle from the elevator platform to the entranceway receiving platform. The particular apparatus chosen to perform these functions incorporates an endless chain which mounts what is called a "traveler" and which traveler pivotally mounts on moveable arms a pair of spaced and rotatably mounted spindles adapted in a raised position to engage the left front wheel of the vehicle during parking and to engage the left rear wheel of the vehicle during unparking. Raising and lowering of the traveler spindles is controlled by a piston and movement of the chain is controlled by a drive motor. When actuated, the piston moves the spindles into position and which action closes a further switch to actuate the chain drive motor causing the vehicle to be moved forwardly onto a mating elevator platform which movement upon completion causes the traveler arms and spindles to be lowered and returned to the entranceway position by appropriate sequential actuation of the referred to piston and chain drive motor. During unparking a separate entrance mover is employed to raise the spindles at the elevator platform, engage the left rear wheel, move the vehicle to the receiving platform, lower the spindle and then be returned to the elevator platform position. Guidance for the left wheels of the vehicle when moving between the entranceway receiving platform and the elevator platform is provided by a pair of guide bars whose position is controlled by a piston and whose action is coordinated with the traveler, chain drive, etc. One bar is raised and guides the wheels during parking and the other bar is lowered. During unparking the bar that was lowered during parking is raised for guiding the wheels and the other bar is lowered.

ELEVATOR OPERATION

Before proceeding with a description of a normal elevator operation mention is made of the elevator platform and its lateral shift capability. In this regard the method and system of the invention are unique in introducing the concept of using elevators whose platforms are detachable and laterally moveable at the ground or base level from the elevator, per se. The elevator platform mounts four wheels and at the base level the elevator may be lowered so that the platform wheels engage a pair of rails running laterally from one or both sides of the elevator and support the elevator platform which is detached and free to move laterally of the elevator. Thus, if a vehicle being unparked has priority use of an elevator and a vehicle being parked is on the elevator platform for such elevator the platform having the vehicle may be shifted laterally off the elevator and simply held at base level and an empty platform moved onto the elevator and positioned to handle the vehicle being unparked after which the elevator platform having the vehicle being parked may be moved back over the elevator and positioned as required. The elevator platforms are powered and individually controlled to accomplish these functions. The concept of making each elevator platform detachable from the elevator itself and of making the elevator platform moveable laterally thus provides a means for rapidly resolving conflicts between incoming and outgoing traffic at the base level and enables the same elevator to rapidly switch from serving incoming to serving outgoing traffic and vice versa. Of at least equal importance is the ability to move vehicles from one aisle to another by use of the elevator platforms.

Another advantage afforded by the concept of making the elevator platform detachable and shiftable is that the method and system of the invention adapts to a wider variety of structural configurations. For example, in a preferred embodiment each entranceway aligns with a particular elevator. However, building conditions may require or make more economically feasible an arrangement where an entranceway aligns not with an elevator, per se, but with an elevator platform position. Thus, during parking an incoming vehicle could be moved from the entranceway onto the elevator platform and then the elevator platform shifted laterally to a position over the elevator for movement to the selected floor level. During unparking a reverse operation could be followed. While some applications of the invention may use conventional elevators having the platforms permanently fixed and may not require the elevator platform detachable and lateral movement feature described it can be seen that substantial operational and architectural variations not heretofore available are made possible by such feature. Furthermore, as later described in detail the invention system mechanically coordinates the elevator platform shiftable with the operation of the entrance mover and with normal elevator operation.

Referring back to a description of a normal elevator operation, the vehicle to be parked is moved onto the elevator platform by the entrance mover and the elevator in order to orient the vehicle for subsequent discharge rises slightly, rotates 180° and moves to the selected floor level for parking. Of course, during such a normal operation the elevator platform and elevator

are effectively mechanically attached and move together as an integral unit and they remain joined until such time as the elevator drops its elevator platform on the mentioned rails and places the weight of the platform on the rails.

AISLE MOVER

To continue the summary of the invention it will be assumed that an elevator has brought a particular vehicle to a particular floor level and in alignment with the aisle serviced by the elevator and the operation required is to move the vehicle down such aisle and onto a selected storage platform. The aisle clearing operation is discussed later. For now it will be assumed that the aisle clearing operation has been performed and that the selected storage platform is in the appropriate position in the aisle serviced by the elevator. The aisle mover has a base frame which is rail mounted above the elevator serviced aisle and is positionable both above the arriving position of the elevator as well as above any position corresponding to a storage platform position. The base frame of the aisle mover mounts a pair of sub-frames which move back and forth on the base frame. The sub-frames mount pivotal arms supporting bumper pushers, at opposite ends of the base frame and these arms are designed to move from a stored position in which they clear the vehicle to a lowered operational position in which they allow the bumper pushers to engage and effectively grasp the front and rear surfaces of the vehicle in a clamping type action. The base frame is moved over the vehicle to be moved, the arms are lowered by gravity action and then the two sub-frames are moved together by means of a motor and screw arrangement which brings the two arms and their respective bumper pushers into engagement with the front and rear bumpers of the vehicle. Appropriate switches are closed and an electric drive motor mounted on the base frame drives a friction wheel which engages a rail member on which the base frame moves and causes the base frame to move towards the selected storage platform. Upon arriving at a position above the storage platform the base frame will have moved the vehicle upon the storage platform and at this point the base frame electric drive motor stops, sub-frames are moved apart and the arms are raised to a position which clears the vehicle. The aisle mover may now be caused to remain in such position or returned to some arbitrary home position awaiting the need for further movement of a vehicle in the same aisle.

STORAGE CARRIER PLATFORM AND ITS OPERATION

To summarize the construction and operation of the storage carrier platforms it is helpful to think of the process involved in opening an aisleway on a particular floor and in a particular area on that floor. The aisleway should of course be opened as rapidly and safely as possible, and certainly with as few moving parts as possible. Another consideration is that the attendant is outside the machine proper and cannot know where the storage carrier platforms are situated at any one time without a control board of lights or other remote signalling means. As a further consideration, it is not desirable that the attendant have to make deci-

sions as to which carriers must be moved to open certain aisleways. In light of these considerations the invention provides a mechanical system based on employment of two rods for each "bay" which act to position the carriers and are called "positioning rods". Each pair of positioning rods are moved simultaneously in the bay. A "bay" is considered to encompass all of the spaces in a crosswise extending line of spaces. As previously mentioned, the spaces in a lengthwise direction are thought of as being in "rows" with certain rows being designated for moving vehicles and these are thought of as being the "aisles".

One of the positioning rods in each bay is used to move any carrier necessary to be moved to the right to be moved in that direction and the other rod in the same bay is used to move any carrier necessary to be moved to the left to be moved in that direction. Prior to simultaneously moving of the two positioning rods for a particular bay the rods are so oriented that each will connect with and control movement of only certain storage carriers. In this regard, it should be noted that in any movement to open up an aisle it is necessary to move only those storage carriers which are in or upon that aisle and such other carriers as are in the way of such movement of the aisle located carriers.

The means of interconnecting each pair of positioning rods with the carriers necessary to be moved is by means of "selector lugs" which are welded around the perimeter of the positioning rods. Depending on the number of rows in the facility, there are a like number of lugs on each positioning rod. There is in fact a lug for each storage carrier on each positioning rod. One space is left vacant in each lug which allows the rods to be moved without affecting any carrier. Now when a particular positioning rod is rotated into such a pre-determined position and then is moved axially the selector lugs on such rod will interconnect with any storage carrier which is not properly located in relation to the aisle to be cleared. In both the parking and the unparking conditions, only one aisle at a time is opened up in a particular area. This makes it possible to rotate each set of two rods in each bay either from front to back or from back to front, simultaneously in order that all storage carriers which need to be moved laterally are mechanically interconnected to the positioning rods.

The method of causing the positioning rods to rotate to the correct position in order that the specific interconnecting lugs will connect with the storage carriers which need to be moved, is accomplished by two "indexing" rods. The indexing rods index or turn the positioning rods so that they are in the proper position for the interconnecting lugs to mechanically attach themselves to the carrier connectors, or miss the connectors if a carrier is not to be moved.

A pair of indexing rods extend longitudinally of each parking area. One indexing rod acts to simultaneously position all corresponding positioning rods in the area which are used for moving those carriers that are required to be moved to the left. The other indexing rod acts to simultaneously position all positioning rods in the area which are used for moving carriers to the right. The two indexing rods rotate the positioning rods through a gear arrangement and each indexing rod is equipped with an indexing piston operator located near the elevator bay. The action of each respective index-

ing piston is to pull the respective positioning rods through the gears which interconnect the indexing and positioning rods causing them to rotate. Commercially available piston operators are adapted to moving from a zero position to any pre-determined extended position, stopping and returning or going on to an additionally extended position. It is important to note that for each operation to be accomplished, such as clearing a certain aisle in a certain area, the indexing rods are moved to the same identical spot which calls for clearing of that particular aisle. Notwithstanding any prior physical arrangement of the storage carriers by reason of previous movements in a prior operation, the selector lugs when positioned for a new operation automatically compensate and move only those carriers required to be moved in the new operation.

Assuming that the indexing rods have been moved by their respective pistons to index the positioning rods in such a way that the connectors are connected to all the carriers that must be moved for the desired clearing of an aisle. The positioning rods will be held in such position by the indexing rods until the corresponding operation is completed. It should be remembered that all of the positioning rods throughout the area are so positioned whether a vehicle is to be parked or retrieved from the back or the front of the particular area.

Once the positioning rods are all properly indexed and are interconnected to the proper carriers to be moved in the particular operation, the pairs of positioning rods in each bay of the area involved are simultaneously moved, one moves to the right and one moves to the left. In this one simultaneous action, all storage carriers throughout the storage level or area involved which are required to be moved do move and they move at the same time. Those carriers which have to be moved to the left are moved to the left. Those which have to be moved to the right are moved to the right and in one simultaneous action of the positioning rods, which move from their home base, or normal inactive position, to the right and left respectively, the selected aisle is completely cleared from front to back. At this point, the positioning rods come to a full stop, the carriers are all in their desired new locations, and the indexing rod pistons are automatically indexed to return the rotated positioning rods to that position which corresponds with all lugs being free of contact with any of the carriers. The positioning rods once so repositioned are returned to their home base by means of counterweights connected to the respective rods and acting through gravity on each of the position rods.

Reference is next made to a description of the power means for moving the positioning rods and their attached carriers during an aisle clearing operation and which uses a system of components referred to as an "alignment guide". The alignment guide incorporates a rotating arm which is mounted on a circular geared wheel that is capable of rotating back and forth in a 180 degree arc. The outer end of each arm on each respective alignment guide is attached to a respective pair of positioning rods through flexible connectors, e.g. cables or chains, operating over appropriately arranged pulleys. The alignment guides are so arranged that as the respective arms revolve through a 180° arc each rod of the respective pairs of positioning rods will be

moved one row width. There is an alignment guide, as described here, for each bay and such alignment guide mates with a respective pair of positioning rods for such bay. All the alignment guides for all the bays in a given level or area rotate simultaneously and the simultaneous movement of the positioning rods in such area is actually caused by the respective alignment guides rotating.

Each alignment guide in a particular area is activated by its own respective alignment rod. The alignment rod is a simple flat bar having a rack of teeth which can be made to engage the teeth on the alignment guide wheel to which the alignment arm is attached. Thus, whenever the alignment rod is moved with the alignment rod rack teeth and alignment guide wheel teeth engaged the alignment guide wheel will be moved. From this, it can be seen that the positioning rods which were originally indexed simultaneously over the whole of the selected area also cause all of the required storage carriers to move simultaneously throughout the area by the movement in unison of the alignment guides in that area.

Now since it is not desired to clear an aisle from front to back, every time any car is to be removed it is helpful and economical to have a system which moves only those storage carriers, to clear the aisle only as far back in the storage area as is required. Therefore, according to the invention, an engaging mechanism causes each respective alignment rod to engage its respective alignment wheel only when necessary. Obviously, if the teeth of the alignment rod rack are not engaged to the teeth of the alignment guide gear wheel no action in the alignment guide will take place and no action of the corresponding positioning rods will take place.

To control engagement and disengagement of respective alignment rods and guides, an engagement rod is provided for each alignment rod and is aligned parallel with the respective alignment rod. Each respective engagement rod is activated or indexed previous to the movement of the corresponding alignment rod and the position of the engagement rod determines engagement of the alignment rod with the alignment guide wheel. Thus, the engagement rod positions ultimately determine which pairs of positioning rods are moved. Each mating alignment guide rod and engagement rod set travel through what is called an engagement holder. The engagement holder is equipped with springs which normally hold the alignment rod away from the alignment guide wheel and the respective alignment rod rack teeth and guide wheel teeth are therefore disengaged. To control teeth engagement each engagement rod has a pre-determined set of projections spaced along its length and which force the compression of the springs and the alignment rod rack to move so as to engage the corresponding guide wheel gear teeth. The engagement rod thus is designed with appropriate thickened spots or protrusions which are spaced so as to allow the selected alignment guide and rod to engage and each particular engagement rod holds this position until the alignment rod has operated the alignment guide and has returned to its home base or inactive position, along with the action of the respective positioning rods returning to their home base or inactive positions. The respective engagement rods are also returned to their respective home base or non-active positions.

Indexing type pistons are employed to control the positioning movements of the engaging rods. Therefore, the piston operation of an engagement rod is similar in all respects to the piston operation of an indexing rod. That is, the engagement rod piston, like the indexing rod piston, indexes or positions the engagement rod for the selected teeth engagement and movement of the alignment guides and then returns the engagement rod to its home base where all tooth engagement is eliminated.

Upon the engagement of each respective alignment rod with its respective alignment guide wheel, the alignment rod is activated through a heavy duty piston located near the elevator bay which pulls the alignment rod through the engagement holder and turns the alignment guide wheel and the corresponding arm in the bay where the alignment guide has been engaged by the alignment rod. After this operation, the alignment guide is rotated back to its home position through the operation of the previously mentioned counterweights and the positioning rods are returned to their home base.

Two major operations have now been described. It has been shown how the positioning rods are indexed to clear a specific aisle and it has also been shown how the alignment rods are engaged with the alignment guides to move only those storage carriers which are to be moved to clear an aisle as deep as necessary. Once a section of aisle has been cleared to the depth desired, the operation is completed for the aisle clearing and a second operation takes place which is a duplicate of that already described with the exception that the positioning rods are indexed to move only one specific carrier into position at the head or end of the cleared section of aisle and the engagement rod is indexed to engage only the one set of positioning rods required to move the one carrier either to the right or left to its desired spot. The particular carrier being referred to here is the carrier on which a vehicle is to be stored or from which a vehicle is to be removed. It is important to realize that this second operation takes place, notwithstanding that the carrier might be already correctly spotted. Also to be observed is the fact that we are concerned here with an internal part of the machine and the operator does not know that the particular carrier is correctly spotted and in fact does not have time to check even a control board which might be installed with appropriate signalling means for this purpose. It is deemed highly desirable to complete the two complete operations each and every time for both parking and unparking, since if the carrier in the second operation is correctly spotted there is no wear and tear on the machine with the exception of the rotating of the positioning rods and the engaging of the alignment rods which will make one complete cycle or movement of the positioning rods but will move no carriers whatsoever. The system does insure that the vehicle will be parked or stored upon the proper storage carrier and the correct car will be retrieved from the storage carrier and eliminate the inevitable human error attached to operator decisions.

BUILDING STRUCTURE

FIGS. 48 and 49 illustrate how the machine components of the invention adapt to properties having restrictive boundary line configurations. While such

property restrictions may reduce the number of storage positions available the machine adapts to such odd configurations and if the restriction or intrusion exists only at one level it affects only that particular level. FIG. 49 shows how the entrance area may be arranged when there is a property restriction in this area. Since the transfer carrier 107 is capable of lateral movement the entranceways 76 are not required to align with the machine aisles or the elevators 130. This greatly enhances the possibilities of adapting the machine to various existing property configuration.

In concluding the summary of the invention brief reference will be made to the building structure employed in the embodiment disclosed with the understanding that other kinds of structures are equally suited. In particular, a three level structure is employed having one ground or base level and two upper levels. Three entranceways are used and the two upper levels provide parking spaces both above the entranceways as well as on the main floor levels. The entranceways are spaced one aisle width apart and the supporting columns are arranged such that the aisles and rows are free of column obstruction and allow unobstructed movement of the vehicles down the full length of the aisles and unobstructed lateral movement of the storage carrier platforms in the bays. The elevators are arranged to service all portions of the two upper floors and the aisle movers on the two upper floors are adapted to move the vehicles both in the main floor areas as well as in the aisles which physically reside above the entranceways. The elevators, which are provided for transporting the vehicle up and down as any normal elevator to the desired level, are so designed that the vehicle may be stored in back of the elevator or in front of the elevators. Every level of parking or area of parking that is contiguous is identical in operation with every other level. Every level is completely independent of every other level. In other words, the opening up of aisleways and the spotting of storage platforms at ends of aisleways can be happening in every parking area on every level, all simultaneously.

DESCRIPTION OF DRAWINGS

FIG. 1 is a plan diagram of a typical main or base level.

FIG. 2 is a plan diagram of a typical upper or lower level.

FIG. 3 is a typical longitudinal section of the levels shown in FIGS. 1 and 2.

FIG. 4 is a partially cut away plan view of a typical main or base level showing the reception area and the machine elements in a typical configuration.

FIG. 5 is a plan view of the combination reception and retrieval platform.

FIG. 6 is a cross-section through the reception and retrieval platform shown in FIG. 5 with certain parts in detail and others in outline form.

FIG. 7 is a plan view of the transfer carrier.

FIG. 8 is a side view of the transfer carrier.

FIG. 9 is a typical cross-section through the transfer carrier.

FIG. 10 is a plan view of a typical elevator unit.

FIG. 11 is a side view of the transfer carrier with the elevator arms in a retracted position.

FIG. 12 is an end view of the typical elevator unit.

FIG. 13 is a plan view of the two entranceway movers used for parking and retrieval movements and without the transfer carrier.

FIG. 14 is a longitudinal section taken along line 14—14 of FIG. 13 through the entranceway mover showing the entranceway mover in its raised position.

FIG. 15 is a longitudinal section on line 15—15 of FIG. 16 through the entranceway portion of the entranceway mover to show the guide units of the reception platform and the traveler assembly at the non-drive end.

FIG. 16 is a cross-section through the reception platform and the entranceway mover on line 16—16 of FIG. 15.

FIG. 17 is an elevation of a portion of the entranceway mover illustrating its raised and lowered position on line 17—17 of FIG. 16.

FIG. 18 is a plan view of the traveler portion of the entranceway mover illustrated in FIGS. 15, 16, and 17.

FIG. 19 is an elevation view of the traveler portion of the entranceway mover shown in FIG. 18.

FIG. 20 is a partial plan of typical bays in the storage area of the machine with the platform carriers omitted.

FIG. 21 is a transverse section taken on line 21—21 through the typical bays shown in FIG. 20.

FIG. 22 is a longitudinal section taken on line 22—22 through the typical bays shown in FIG. 20.

FIG. 23 is a plan section view taken on line 23—23 of FIG. 24 showing the control mechanism at the intersection of the indexing rods with the positioning rods.

FIG. 24 is an elevation section through the positioning rods and indexing rods shown in FIG. 23.

FIG. 25 is a section taken on line 25—25 of FIG. 23 taken through the indexing rods looking toward the positioning rods shown in FIGS. 23 and 24.

FIG. 26 is a detail elevation of the carrier positioning connectors and the positioning rods with their selector lugs.

FIG. 27 is a cross-section along line 27—27 of FIG. 26 taken through a positioning rod with the selector lugs and showing in elevation the carrier positioning connector of FIG. 26.

FIG. 28 is a plan view of the carrier positioning connector shown in FIGS. 26 and 27.

FIG. 29 is a plan view of a portion of the positioning rods.

FIG. 30 is a plan view of a positioning rod connector link shown in FIGS. 26 and 29.

FIG. 31 is a plan detail taken on line 31—31 of FIG. 32 showing the operating mechanism for engaging the alignment guides for moving the positioning rods.

FIG. 32 is a detail section taken along line 32—32 of FIG. 31 through the operating mechanism shown in FIG. 31.

FIG. 33 is a detail cross-section taken along line 33—33 of FIG. 32.

FIG. 34 is a plan view of a typical carrier and a portion of the adjacent elements.

FIG. 35 is a longitudinal section taken on line 35—35 of FIG. 34 showing the carrier and its supports and tracks shown in FIG. 34.

FIG. 36 is a cross-section taken on line 36—36 of FIG. 34 taken through a typical carrier and a portion of an adjacent carrier showing the carrier on the rails.

FIG. 37 is a cross-section taken on line 37—37 of FIG. 34 taken through a typical carrier and a portion of an adjacent carrier showing a portion of the operating mechanism to position the carriers.

FIG. 38 is a plan view of a portion of the typical parking bay with the carriers omitted for clarity and the aisle mover positioned in the bay.

FIG. 39 is a transverse cross-section taken along line 39—39 of FIG. 38 through the typical bays shown in FIG. 38 with the aisle mover in the lowered position.

FIG. 40 is a plan view of one-half of the aisle mover with the aisle mover located in its typical lowered position.

FIG. 41 is a cross-section taken on line 41—41 of FIG. 40 through the aisle mover shown in FIG. 40.

FIG. 42 is a schematic diagram of the pulley arrangement to raise and lower the pusher unit for the aisle mover shown in FIGS. 38, 39, 40, and 41.

FIG. 43 is a detail of the pivot end mechanism of the bumper pusher arms.

FIG. 44 represents a typical assembly of three alignment guides, corresponding positioning rods, indexing rods, engagement rod and alignment rod.

FIG. 45 is a detail of the selector lugs on the left moving positioning rod.

FIG. 46 is a detail of the selector lugs on the right moving positioning rod.

FIG. 47 is a composite view of both positioning rods with the selector lugs shown in their proper arrangement.

FIG. 48 is a plan diagram of a typical entry, main or base level, illustrating the adaptation of the machine to properties with irregular shapes or restrictions along the perimeter.

FIG. 49 is a plan diagram of a typical entry, main or base level, illustrating the adaptation to a restricted entrance area and other property line restrictions.

FIG. 50 is a generalized schematic diagram of a control system for the invention.

DESCRIPTION OF PREFERRED EMBODIMENTS

BASIC STRUCTURE

The components making up the system or machine of the invention may be enclosed by suitable walls attached to the machine for support if desired, or the machine may be installed in an existing structure or the components may be assembled and left exposed in suitable climates. Furthermore, the basic structure readily accommodates to irregular as well as regular shaped lots.

Referring to FIGS. 3, 4, 20, 21, 22, 38, and 39, the basic machine structure is composed of columns 59 which are normally arranged in a rectangular pattern and whose locations define the aisles and rows. Transverse beams 60 and longitudinal beams 61 at the exteriors are supported by columns 59. Longitudinal beams 62 and 63 are supported by transverse beams 60. Transverse beams 64 are supported by longitudinal beams 61, 62, and 63. Aisles shown as 66 in FIGS. 1, 2, 4, 20, 21, 38, and 39 are composed of combination longitudinal beams 62 and 63. The combination beam 62 is composed of a guiding flanged runway member 67 attached to its support member 68 as shown in FIG. 39, and the combination beam 63 is composed of a non-

guiding runway member 69 attached to its support member 70. The typical structure is further shown by plan view in FIG. 38, and by cross-section view in FIG. 39 showing clearly the primary guiding runway members 62 of the aisle system with the raised and beveled sides for guiding the vehicle through its own running wheels. The non-guiding runway member 63 for the aisle system is shown with its wide width to accept different size vehicles with the varying tread widths and for strength this runway 63 has the edges turned down since no provisions for guidance are required.

FIGS. 20, 21, 22, 35, and 36 illustrate the combination transverse beams 64 composed of a guiding flanged runway member 71 attached to its support member 72. Recalling that the vehicles are each individually stored on transversely moveable platforms the beams 64 provide the support and guidance for the transverse movement of the storage platforms 160 shown in FIGS. 4, 34, 35, 36, and 37. The raised sides of members 67 and 71 are omitted and shaped to eliminate conflicts at their intersections and with beams 60 and 63, as shown in FIGS. 20, 21, 22, 35, and 36.

At the reception area shown in FIG. 4, columns 75 are widely spaced to provide a reception area suitable for vehicular approach, customer movement, attendant service, and customer retrieval of the vehicle. At the main level, entranceways 76 are provided of concrete or similar material and have islands 76a which are raised approximately 4 inches to provide wheel guidance for incoming and outgoing vehicles. Customers or public areas are shown in FIG. 4 as 77 and have floors of concrete or similar material which are raised approximately 6 inches above the entranceways 76. The public areas 77 are separated from the machine proper by walls 78 constructed of any suitable material and by moveable gates 79 which are normally opened only upon the parking or retrieval of a vehicle and are controlled by photocells, magnetic switches, or the like which are well known in the art.

RECEPTION UNIT

The so-called reception unit 41 is shown in FIGS. 4, 5, 6, 15, and 16. Reception unit 41 comprises a metal framed unit upon which the operator of the vehicle drives, stops the vehicle, and leaves the vehicle for parking by the machine attendant. Reception unit 41 is also used in the reverse process during unparking where the vehicle is retrieved from the machine and delivered to the original operator.

As shown in FIGS. 4, 5, 6, and 16, the reception unit is designed to provide guidance for the wheels on the left side of a vehicle through wheel runway 42 for incoming vehicles to be parked and through wheel runway 43 for vehicles being unparked and returned. As shown in FIGS. 4 and 5, special openings 44 and 45 are provided in wheel runways 42 and similar openings 46 and 47 are provided in wheel runways 43. The openings 44 and 45 are matched respectively with guide openings 44a, 45a in the vertical side members 51, of runway 42 as shown in FIG. 15. Similar guide openings 46a and 47a are matched with the openings 46 and 47 in runway 43. The purpose of the openings will be later described in connection with a separate unit to be referred to as the "entranceway mover." The

framework of the reception unit 41 is shown in FIG. 6 where posts 48 support cross beams 49 which in turn support longitudinal beams 50 and vertical wheel runway plate supports 51. The longitudinal beams 50 in turn support the center metal plate 52.

In order to provide accurate guidance for the selected wheels on the left for an entering vehicle, horizontal railing 53 is provided, and for the accurate guiding of the vehicle being retrieved horizontal rail 54 is provided as shown in FIGS. 5, 6, and 16. FIGS. 5 and 6 show the openings provided in the reception unit 41 for passage of railings 53, 54 and are indicated by the numbers 53a and 54a. As shown in FIGS. 6 and 16, these horizontal guidance rails 53 and 54 are interconnected through respective verticals 55 and a pivot bar 56. The pivot bar is pivoted at the center of cross beam 49 and by pins connected to the lower portion of the support verticals 55 allow either guidance rail 53 or guidance rail 54 to be in the up or guiding position while the other is in the down position. The vertical support members 55 are aligned by sleeves 56a.

The operation of the reception unit 41 in the receiving of a vehicle to be stored in the machine is as follows. The left hand horizontal guidance rail 53 is positioned in the up position which will accurately guide the left wheels of the incoming vehicle while the horizontal guidance rail 54 is depressed to the non-guiding position thereby allowing any vehicle of varied tread width to be accommodated. Conversely upon the retrieval of a vehicle from the machine during unparking the horizontal guidance rail 54 is raised to the up position to provide accurate guidance of the left wheels of the vehicle being returned, while the horizontal rail 53 is in the depressed non-guiding position, again to accommodate all varying tread widths of vehicles. The normal position or home base of the horizontal guidance rail 53 is in the up position due to the heavier portion of pivot bar 56 being attached to the support vertical 55 attached to guidance bar 54 which retains the rail 54 in the lowered position due to gravity. Horizontal guidance rail 54 is automatically raised by the activation of a piston 57, FIGS. 6 and 16, by electrical interlock with the entranceway mover 80 to be later described and such activation is coordinated with the return of a vehicle to the reception unit 41. Guidance rail 54 thus provides the final accurate wheel control for the vehicle being delivered to the customer area.

ENTRANCEWAY MOVER

As previously stated the entranceway mover provides means for grasping the left front wheel during parking and the left rear wheel during unparking for moving the vehicle between the entranceway and the elevator. Its details will be next described.

The entranceway mover 80 is illustrated in FIGS. 4, 5, 6, 13, 14, 15, 16, 17, 18, and 19. The entranceway mover includes a basic steel framework consisting of a plurality of regularly spaced supports 81 supporting a longitudinal beam 82 as shown in FIGS. 13, 14, 15, and 16. This framework supports track 83, brackets 84 and 85, and the conveyor chain 86 through the sprocket drive wheel 87 and tail wheel 88, as well as idlers 89 supporting the chain as illustrated in FIGS. 14, 15, and 16. The track 83 in turn supports the wheels 90 of the traveler 91 as shown best in FIGS. 15, 17, 18, and 19.

Attached to the framework supports 81 through multiple arms 92 is the main spindle guide unit 93. The arms 92 are pivoted on pins 92a extending through brackets 84 and 85 (FIG. 16) and to the guide unit 93 by means of pins 94 extending through brackets 95 (FIG. 16). The raising and lowering of the guide unit 93 is controlled by means of a suitable piston 96 shown in FIG. 14 and which is connected to one of the arms 92 so as to move the arms in synchronism. FIG. 16 illustrates a section through the entire entranceway mover with the main spindle guide unit 93 in the raised position and also illustrating by dotted lines its lowered position. This section also shows the relationship of this unit to the reception unit 41.

FIGS. 15, 16, 17, 18, and 19 illustrate the traveler 91 which is composed of the main member 97, parallel arms 98 and horizontal tie bar 99. These members are interconnected to spindles 100 and 101 through pins 102 and 103. As previously stated the traveler 91 is supported by wheels 90 using pins 103 as axles and member 97 is attached to and becomes a moving part of chain 86 as clearly shown in FIGS. 15, 17, and 18. Wheels 90 roll in and are guided by track 83 (FIGS. 15, 16). An additional thrust bar 104, and wheels 105 and 106 are mounted on pins 102 as shown in FIGS. 16 and 18. The wheels 105 and 106 roll in the special track section 93a (FIG. 16) of the main spindle guide unit 93 as shown in FIGS. 16 and 17. The thrust bar 104 provides the resistance to the forces applied to the spindles 100 and 101 in the horizontal plane while the guide unit 93 provides resistance in the vertical plane through the wheels 105 and 106. From FIGS. 14, 15, 16, 17, 18, and 19 it can be seen that the traveler 91 is free to be transported along the track 83 in either the raised or lowered position without interference with the reception unit 41 or with the transfer carrier 107 shown in FIGS. 7, 8, and 9, and to be later described.

The main spindle guide unit 93 is raised or lowered only when the traveler 91 is at one of the extreme ends of its travel. Normal operation of the entranceway mover 80 for the initial parking operation calls for raising of the main spindle guide unit 93 while the traveler 91 is at the reception end of its travel and which is its home base. The spindles 100 and 101 and pins 102 are free to raise into the overlapping position with the reception unit 41 through the guide openings 44a and 45a, shown in FIG. 15 and the special openings 44 and 45 in wheel runway 42 shown in FIGS. 4 and 5. FIGS. 15 and 16 illustrate the respective locations of spindle 100 on one side of the vehicle's left front wheel 108 and spindle 101 on the other side of wheel 108. With the traveler 91 so retained in this raised position by the action of piston 96 on the arms 92 connected to the guide unit 93 the traveler 91 is transported into the parking machine by means of the motor 109 (FIG. 14), drive sprocket 87, and chain 86 shown in FIGS. 13, and 14, with the spindle 101 interacting with the lower portion of the vehicle wheel 108 and thereby also transporting the vehicle into the parking machine and onto the transfer carrier 107 shown in FIGS. 4, 7, 8, and 9 whereupon spindle 100 acts to stop the wheel 108 at the correct position on the carrier 107.

Upon arrival of the traveler 91 into the parking machine with its spindles 100 and 101 respectively located in the proper relationship to the openings 110

and 111 in the wheel runway 112 of transfer carrier 107, and the guide openings 110a and 111a in the vehicle side members of wheel runway 112 as shown in FIGS. 8 and 11, the vehicle has been properly located on the transfer carrier 107 and the main spindle guide unit 93 is returned automatically to its lowered position by gravity and then the traveler 91 is returned to its home base at the reception unit 41 by the reversing of motor 109. For the retrieval of a vehicle there is an essentially identical entranceway mover used in a 180° rotated position. This is illustrated in FIG. 13. In this case, the home base for the traveler 91 is at the transfer carrier 107 end within the machine proper and with the spindles 100 and 101 being raised automatically into position when the vehicle has been previously moved onto the transfer carrier 107 with its left rear wheel in position between openings 113 and 114 shown in FIG. 7. The action of the entranceway mover in retrieving the car from inside the machine and specifically from transfer carrier 107 and moving the vehicle to the reception unit 41 is similar in all respects to the previously described method of moving the vehicle onto the transfer carrier 107 from the reception platform 41.

TRANSFER CARRIER

The carrier 107 provides a platform for receiving the vehicle into the machine, supporting it during rotation by the elevator and during lifting and lowering. The transfer carrier 107 is illustrated in FIGS. 4, 7, 8, 9, and 11. Carrier 107 is supported by four wheels 115 which in turn is supported and guided by rails 116 and 117 which allows the carrier 107 to freely move laterally to mate with different aisles or entranceways on the main level to rest between elevators or to mate with a particular elevator as desired for special situations. These rails 116 and 117 are illustrated as U shaped members to be used in conjunction with the flat tread wheels 115. The carrier is controlled in the lateral movement yet is free to be raised and rotated by the hydraulic piston elevator 130 shown in FIGS. 10, 11, and 12 and to be described in detail later. Carrier 107 embodies a specially designed platform composed of a basic framework of structural metal beams 119 running in the longitudinal direction and cross ties 120 and 121 at right angles. The cross ties are attached to and supported by the main beams 119 and are extended to support the vertical plate supports 122 which in turn support the wheel runways 112 as shown in FIG. 9. The longitudinal beams 119 also support the center metal plate 123.

As shown in FIGS. 7 and 8, special openings 110, 111, 113, and 114 are provided in wheel runways 112. These openings are matched respectively with guide openings 110a, 111a, 113a, and 114a in the vertical side members 122. Openings 110, 110a, 111 and 111a are in use when the entranceway mover 80 moves the vehicle into the parking machine as described in connection with the entranceway mover 80. Openings 113, 113a, 114, 114a are in use when the vehicle is being retrieved from the machine.

In order to provide accurate guidance for the selected wheels on the left for an entering vehicle, horizontal rail 124 is provided, and for the accurate guiding of the vehicle being retrieved horizontal rail 125 is provided as shown in FIGS. 7, 8, and 9. FIGS. 7

and 9 show the openings 124a and 125a which are provided in the transfer carrier 107 for rails 124 and 125. As shown in FIGS. 9 and 11, the horizontal guidance rails 124 and 125 are interconnected through their support verticals 126 and the pivot bar 127. Pivot bar 127 is pivoted at the center of cross ties 120 and 121 and pin connected to the lower portion of support verticals 126 in such a way that either guidance rail 124 or guidance rail 125 is in the up or guiding position while the other is in the down position. The support verticals 126 are aligned by sleeves 126a shown in FIG. 9. The operation of the transfer carrier guidance rails in the parking and retrieval sequences is similar to that previously described for the reception unit. It is to be noted that guide openings 110a, 111a, 113a, and 114a for the axles 102 and openings 110, 111, 113, and 114 for the spindles 100 and 101 of the entranceway mover 80 are provided in both of the wheel runways 112, since the transfer carrier 107 is not only capable of transverse movement but 180° rotational movement also. In all cases openings 110 and 111 are used in the parking sequence while the openings 113 and 114 are used in the retrieval sequence. The lateral movement of the carrier 107 is by means of an electrically driven reversible motor 128 acting through standard gears to turn friction driving wheel 129 which is in contact with the rail 116 or 117 to move the carrier 107 in a left or right direction as desired.

ELEVATOR

One unique feature of the invention is the fact that the transfer carrier 107 which acts as the elevator platform and the elevator proper are disengageable one from the other. This feature thus gives the transfer carrier freedom to shift laterally when disengaged and also allows the same transfer carrier to serve more than one elevator aisle and entranceway. The generally conventional elevator is now described.

The elevator 130 is shown in FIGS. 1, 2, 3, 4, 10, 11 and 12. Elevator 130 utilizes a standard hydraulic cylinder piston 131 with special arms 132 extending outward as shown in FIG. 10. Arms 132 have lifting ears 133 which are adapted to engage beams 120 of the transfer carrier 107 when in the lifting or lowering operation. Arms 132 are also equipped with a rotating mechanism which operates through an electric motor 134 acting through standard design gears to rotate the transfer carrier 107 through 180°. Such rotation reverses the direction of the incoming vehicle and orients it properly for heading out of the entranceway during an unparking operation. Elevator 130 is controlled so that it rises to a level approximately 6 inches above the main level each time before it rotates which rotation eliminates the conflicts of carrier 107, with the reception unit 41 and the other basic machine structure members.

THE AISLE MOVER

The so-called "aisle mover" is next described and it can be said to generally serve the purpose during parking of moving the vehicle from a transfer carrier positioned by the elevator down a cleared section of aisle and onto a storage carrier. During unparking the aisle, mover moves the vehicle from the storage carrier down a cleared aisle and back onto the transfer carrier.

After the vehicle has been moved from the reception unit 41 into the parking machine by the entranceway mover 80, onto the transfer carrier 107 and the carrier 107 with the vehicle residing thereon, has been raised and rotated 180° then lifted or lowered by means of the elevator 130 to the desired parking level the vehicle is moved by the aisle mover 135 along aisle 66 as shown in FIGS. 1, 2, 4, 38, and 39. The aisle mover 135 which is shown in FIGS. 38, 39, 40, and 41 is a special vehicle mover one of which is provided for each of the aisles 66 illustrated in FIGS. 1, 2, 4, 38, and 39. The aisle mover 135 has a basic frame 136 shown in FIGS. 38, 39, 40, and 41 which is supported by flanged wheels 137 which in turn are supported by and guided by rails 138 on each side of each aisle 66 as shown in FIGS. 20, 21, 22, 36, 38, 39, 40, and 41. Rails 138 are continuous on each side of each aisle 66. Mounted on this frame are two separate subframes 139 shown in FIG. 38 and in more detail in FIG. 40. The two sub-frames 139 are horizontally mounted between the main longitudinal frame members of frame 136 and are supported at the interior ends by flanged wheels 140 which roll and are guided by the rails 141 attached to the longitudinal main frame of frame 136 and are supported near the center by the transverse brace 136a of frame 136 as shown in FIGS. 38, 40, and 41. Wheels 142 attached to frame 136 provide additional guidance as the sub-frames 139 move horizontally.

Frame 139 supports a bumper pusher mechanism consisting of bumper pushers 144, the side arms 145, and connecting rod 146, the front brackets 147 supporting the pulley wheels 148, and the piston 149 mounted on support brace 150, all shown in FIGS. 38, 39, 40, and 41.

In operation, the aisle mover 135 is propelled by electric motor driven trolleys 151 of standard design in which the driving action is from a motor through a speed reduction to spring loaded rubber tired wheels 152 which roll against the beam 138 shown in FIGS. 38, 39, 40, and 41. In an unparking operation, the aisle mover 135 is propelled along the aisle 66 until it reaches a position directly above the storage carrier 160, later described, upon which the vehicle to be retrieved is stored. The aisle mover 135 is stopped, bumper pushers 144 attached to the sub-frames 139 are lowered through the retraction action of piston 149 which allows the connecting member 146 to retract the piston 149 through the gravity action of the heavy bumper pusher 144 and its side arms 145, and dropping to the full lowered position, as shown in FIGS. 39, 40, and 41. The operation of lowering of the bumper pushers 144 and their interconnection to the tie bar 146 through the cables 154 and their movement over the single pulleys 148 and double pulleys 155, are shown in FIGS. 40, 41 and 42. The tie bar 146 is connected by pin 156 arrangement to the bumper pusher side arms 145 and this pin 156 slides horizontally along the openings 157 in the frame 139 as shown in FIGS. 41 and 43 as bumper pushers 144 are lowered into position. After the bumper pushers 144 have been lowered as described above, then through the action of motor 158 and its interconnection through reduction gearing and opposite threaded rod 159, both sub-frames 139 on each end of the aisle mover 135 are simultaneously pulled toward the center of the aisle mover 135 which

causes the bumper pushers 144 to also move toward the front and rear bumpers of the vehicle through their interconnecting parts previously described and as shown in FIG. 41. Upon both bumper pushers 144 coming in contact with the respective front and rear bumpers of the vehicle, a pressure switch, not shown, is activated and motors 158 are stopped. The opening of the pressure switch also initiates the operation of the aisle mover propelling motors 151 to move the vehicle along the aisle 66 from a storage carrier 160 to the transfer carrier 107. Upon reaching the transfer carrier 107, the aisle mover 135 stops, the bumper pushers 144 move horizontally back to their fully opened position through the reverse action of motor 158 acting on the rod 159. When the bumper pushers 144 are in their fully opened position the pistons 149 are activated automatically by appropriate mechanism, not shown, to move the connecting rods 146 inward within the sub-frame 139 which raises the bumper pushers 144 to their fully raised position as shown in FIG. 41 by the dotted lines. Parking of a vehicle involves a reverse procedure.

TYPICAL STORAGE CARRIER

As previously mentioned each vehicle when stored resides on a storage carrier platform. Each platform is laterally moveable and can be brought into alignment with a selected aisle for parking and unparking and then moved laterally off the aisle when and as desired. The description now proceeds to the construction and then to the positioning of the carriers.

The typical storage carrier platform 160 is shown in FIGS. 4, 34, 35, 36, and 37. Storage carrier 160 includes two runways 161 and 162 which are separated and supported by structural members 163 which members also mount the wheels 164 on which the platform is supported for lateral movement. The primary runway 161 provides the guidance for the wheels of the vehicle with its raised and sloped sides. The secondary runway 162 allows for complete variation in the tread distances of the vehicle wheels. The sloped and raised sides on runway 162 are primarily for strength and not as a guidance feature. Near the center of the storage carrier are two additional structural members 165 and cross supports 165a(FIG. 26) which give additional lateral bracing to the runways and also provides the structural support for the positioning connectors 166 and 167. The storage carriers 160 are completely free rolling and are moved only by the positioning rods 168 and 169 which engage connectors 166, 167 as later explained. The fronts of the storage carrier runways are sloped as indicated by sections 161a and 162a which permits the aisle mover 135 to push the vehicle along the aisle 66 and up and onto the storage carrier 160.

OPERATION OF POSITIONING THE CARRIERS

Recalling that the invention provides means for clearing any selected aisle section in any area by lateral shifting of the individual storage carrier platforms, the operation of shifting the storage carrier platforms can be considered to involve two operational phases. One phase of operation is directed to the manner in which the positioning rods are indexed and the other phase of operation concerns the actual physical connecting of individual storage carriers and particular positioning rods in particular bays. Assuming that an aisle section is

to be cleared in a particular parking area and this aisle section extends over the entire length of the area it is necessary to index each pair of positioning rods for each bay in that area except for the last bay and then to clear the aisle section. Following this the storage carriers in the last bay are shifted by indexing the positioning rods in such last bay and then using such positioning rods for appropriate lateral movement of the storage carriers. In the description next to follow attention will first be directed to the mechanism which connects the individual storage carriers to the individual positioning rods. After this mechanism has been explained the description will next proceed to an explanation of the mechanism employed to index and move the positioning rods. In connection with both descriptions it should be kept in mind that each bay contains a set of storage carrier platforms and a pair of positioning rods. Since the operation that takes place in one bay is the same as what takes place in another bay the following description is limited to one such typical mechanism in a single bay. The reader may find it helpful to review the general summary of the invention for a further overall view of the operation of positioning the storage carriers before considering the detailed description next to follow.

The operation of the positioning connectors 166 and 167 can be understood if reference is first made to FIGS. 34, 35, 37, 26, 27, and 28. The connectors 166 are used only for moving the storage carriers 160 to the right by means of the positioning rods 168 and the connectors 167 are used only for moving the storage carrier 160 to the left by means of the positioning rods 169. A set of selector lugs 170 are mounted on each of the positioning rods 168 and 169 and are engaged with the connectors 166 and 167 to move the storage carriers 160 when by appropriate rotation of the rods 168 and 169 working sectors of selected lugs 170 are brought into operative positions. This action engages a particular sector of a particular selector lug 170 with the corresponding connector 166 and 167 if a particular storage carrier 160 is to be moved. This engaged condition can be readily seen in FIG. 26, while FIG. 27 shows the lugs 170 prior to rotation with none in the engaging or upright position.

Both positioning rods 168 and 169 have identical selector lugs attached however they are in reverse order as can be seen by referring to FIGS. 45, 46, and 47. Positioning rod 168, as noted in prior description, is used to move the storage carriers to the right only and positioning rod 169 is used to move the carriers to the left only. Referring to FIG. 27 it can be seen that the positioning rod 168 is in its unconnected position. When the positioning rod 168 is rotated through its interconnector with the indexing rod 171 the rotation as illustrated is in a counterclockwise manner. All storage carriers to be moved may only be moved laterally if there is a space available. Otherwise, all the storage carriers to the right of the selected carrier desired to be specifically located must be moved simultaneously to provide this space. By referring to FIG. 27, 46 and 49 it can readily be seen that with the first increment of rotation the selector lug 170a only will interconnect to the connector 166 and with the additional second increment of rotation selector lug 170b will interconnect to the connector 166 and the selector lug 170a will

remain connected. The continuation of the positioning rod rotation will consecutively interconnect all selector lugs 170a, 170b, 170c, 170d, 170e, and 170f with those connectors 166 which must be moved to the right to effect the desired repositioning of the originally selected carrier desired to be specifically located.

5 A connector 166 is mounted on the bottom of each storage carrier 160 and each connector has a main body 166a which is shaped as shown in FIGS. 26, 27, and 28. Body 166a has a vertical moving latch 166b which is free to rise when the sloping edge of a selector lug 170 comes into contact with the sloped bottom of the latch, as in FIG. 26. The latch is returned automatically to the down position by gravity when the lug 170 has passed by and into the opening designed for it. This latch 166b allows the selector lug 170 to pass by only when the particular storage carrier 160 is already in the desired location but the horizontal movement of positioning rod 168 must be completed which will place the selector lug 170 into the connector 166.

10 FIG. 26 previously referred to shows two separate connectors 166 for two separate storage carriers 160. By means of the arrangement in FIG. 26 the positioning 15 rod 168 is allowed to be rotated to raise the selector lugs 170 into their engaging position and thence to move automatically through the full movement cycle to the right with the lugs 170 engaging the connectors 166 of those storage carriers 160 which require moving and 20 to have the lugs 170 come into contact with latch 166b just prior to completion of the full movement cycle, force the latch 166b up and out of the way and while allowing the lug 170 to pass into the opening in the connector 166. By referring to FIG. 26 it is clear that this 25 allows the storage carriers 160 to be brought into the correct space relationship as shown with the other storage carriers 160 and the aisleways of the machine. FIGS. 26, 27, and 28 show the latch 166b being provided with a guide 166c at the sides and shoulder 166d at the top which aligns the latch 166b in its upward and downward movement and stops it in the proper location when the lug 170 has passed.

30 The typical rod 168 operation, for moving the 35 storage carrier to the right, having been explained it should be understood that the typical rod 169 operation is the same with respect to moving in the left direction. The same features are provided in connectors 167 with body 167a, latch 167b, guides 167c, and shoulders 167d. The movement of positioning rod 169 is always to the left when the storage carriers 160 are being moved and the latches 167b are provided on the 40 opposite side from latches 166b as can be seen in FIGS. 34 and 35.

45 To continue the description reference will next be made in more detail to the mechanism which indexes and moves the positioning rods. Such mechanism is best shown in FIGS., 4, 20, 21, 22, 23, 24, 25, 26, 28, 29, 30, 35, and 37.

50 The positioning rods 168 and 169 are rotated by indexing rods 171 and 172 respectively as shown in FIGS. 20, 21, 23, 24, 25, and 29, and to engage the desired selector lugs 170 with the positioning connectors 166 and 167 attached to the bottom of storage carrier 160. The positioning rods 168 and 169 are moved horizontally simultaneously in opposite directions by means of the so-called alignment guides 173 shown in FIGS. 4,

20, 31, 32, and 33 which are interconnected to the positioning rods 168 and 169 through flexible cable connectors 174 and 175 respectively as shown in FIGS. 20, 21, 22, 23, 24, 27, 29, and 30.

As has been mentioned above and in the summary of the invention at the beginning of this description, the positioning rods 168, 169 are required to be indexed, i.e. rotated around their respective axis, in order to properly position the selector lugs 170. After being indexed the positioning rods 168, 169 are then required to be moved longitudinally, simultaneously and in opposite directions in order to engage selected lugs 170 with selected storage carrier connectors 166, 167 so as to move certain selected storage carriers 160 to the right and others to the left. Even though as a practical matter all of the positioning rods are put through an indexing operation anytime there is an aisle clearing operation it is neither necessary or desirable to move all the positioning rods longitudinally since in many cases only certain bays or rows are subject to aisle clearing. In order to move only certain positioning rod pairs, each pair of positioning rods is connected through flexible cable connectors 174, 175 to the alignment guide 173 and when the alignment guide rotates it moves the positioning rods. However, rotation of the alignment guide is controlled by selective engagement of gear teeth which are provided on the alignment guide with teeth on a driving member called the alignment rod 178. Alignment rod 178 is powered as later explained and when its teeth are engaged with the alignment guide 173 teeth alignment rod 178 is adapted to rotate alignment guide 173 and thereby move the positioning rods. The tooth engagement between the teeth of alignment rod 178 and the teeth of the alignment guide 173 is controlled by a so-called engaging rod 176 which has a series of spaced cam surfaces along its length that are adapted to engage a surface of the alignment rod 178 and to push and hold the teeth of the alignment rod 178 in engagement with the teeth of the alignment guide 173. The engaging rod 176 is also powered by an indexing piston as later explained so that by controlling the position of the engaging rod 176 its cam surfaces are made to control the engagement and disengagement of the respective teeth of the alignment guide 173 and alignment rod 178 and thereby control whether the positioning rods in a particular bay are or are not moved. Thus, for a particular aisle section in a particular area to be cleared all of the separate engaging rods 176 for each bay in that area are indexed to appropriate positions after the positioning rods 168, 169 have been indexed to bring the lugs 170 into appropriate positions. Next, all of the alignment rods 178 in that same area are activated which causes all of the appropriate lateral movements of the storage carriers 160 to be executed simultaneously after which the positioning rods 168, 169, the engaging rods 176, the alignment rods 178 and the alignment guides 173 are returned to their home base position as later explained.

FIGS. 20, 31, 32, and 33 illustrate how the alignment guide 173 selectively moves the positioning rods 168 and 169 through the action of the engaging rod 176 which acts through the engaging holder 177 to selectively engage the alignment rod 178 with the alignment guide 173 by means of toothed gears 179 on the align-

ment rod 178 and the mating gears 180 on the partial wheel 181 of alignment guide 173. It will be apparent by examination of FIG. 4 that each bay is equipped with the combination of units described above to move the storage carriers 160 selectively. That is, the required lateral movements in each bay may be performed simultaneously but by different units in each bay.

In operation the positioning rods 168 and 169 are rotated to their correct position by means of the indexing rods 171 and 172 simultaneously with the selective engagement of the alignment guide 173 teeth with the alignment rod 178 teeth taking place by means of the engaging rod 176. Once the positioning rods and engaging rods have been properly indexed the alignment rod 178 is then activated by the piston 182 shown in FIGS. 4 and 44 to rotate the alignment guide 173 through 180 degrees which moves both the positioning rods 168, 169 and causes those storage carriers 160 which were previously engaged by the selector lugs 170 to be moved by the positioning rods 168 and 169. It is to be noted that rod 168 moves the storage carriers 160 only to the right while rod 169 moves the storage carriers 160 to the left as shown in FIGS. 4 and 20 which also show the rods 168 and 169 in their home base position. After the completion of the movement of the selected storage carriers 160 the positioning rods 168 and 169 are rotated back to their original position by retraction of the pistons controlling the indexing rods 171 and 172 and return of rods 168 and 169 to their home base position by the counterweights 183 and 184 respectively shown in FIGS. 4, 20, and 21.

To further detail the interconnection of the indexing rods 171 and 172 with the pluralities of positioning rods 168 and 169 respectively reference is directed to FIGS. 23, 24, and 25 which is a large scale detail of the connections shown at small scale in FIGS. 20 and 29. These drawings show indexing rod 171 connected at right angles with positioning rod 168 through toothed gears 171a rigidly attached to rod 171 in a flat configuration, and toothed gear wheel 185 slidably mounted on the positioning rod 168. The gear wheel 185 rotates the positioning rod 168 by the horizontal movement of gears 171a and the spline 168a attached to rod 168. The gear wheel 185 is retained in its position by the retaining member 186 which is secured in turn to support member 187 which is attached to combination beam 63 members 69 and 70 as shown in FIG. 25. As previously shown positioning rod 168 moves horizontally by the rotative action of the alignment guide 173 and then returns to its home base. During this movement of rod 168 it is retained in its pre-selected rotated position by the interaction of the indexing rod 171 and the toothed gear 171a holding the gear wheel 185 which in turn prevents the positioning rod 168 from undesired revolving through spline 168a yet permitting the horizontal movement of rod 168 due to the slideable connection between gear wheel 185, positioning rod 168 and spline 168a. The horizontal indexing movement of indexing rods 171 and 172 is achieved by means of suitable individual indexing pistons 171b and 172b shown in FIGS. 4 and 44 which are of standard manufacture and control mechanism to provide the positive forward, positive reverse and positive hold features for operation of the indexing rods 171 and 172.

The indexing rods 171 and 172 are held in position by idlers 188 and 189 respectively as shown in FIGS. 24 and 25.

The operation of indexing rod 172 to rotate positioning rod 169 is similar in all respects to the description of the rod 171 and positioning rod 168 as just described. To further detail the operation and interconnection of the engaging rod 176, the alignment rod 178 with the plurality of alignment guides 173 reference is made to FIGS. 20, 21, 31, and 32. The engaging rod 176 is positioned horizontally by means of an indexing type piston 176c shown in FIGS. 4 and 44 which may be of standard manufacture and control mechanism to provide positive forward, positive reverse, and positive hold, movements of engaging rod 176 at pre-selected positions. The engaging holder 177 is shown in FIGS. 31, 32, 33, and 44. As best seen in FIG. 31 the engaging rod 176 has a pair of engaging lugs or cams 176a and 176b for each engagement holder. By action of these lugs 176a and 176b the alignment rod 178 is forced over to mesh the toothed gears of 179 with the gears 180 of partial wheel 181. This action is through either lugs 176b or 176a coming in contact with the wedge 190 inside the holder 177. Engagement rod lug 176a is so located that it may be used for the clearing of the selected aisle and lug 176b is so located that it may be used for the positioning of a storage carrier 160 into the cleared aisle ready to receive a vehicle for storage thereon or ready for the aisle mover 135 to retrieve the vehicle. Toothed gears 179 are held clear of gears 180 through compression springs 191 acting upon the rod 178. These springs are retained in guides 192 which also provides guidance for other interrelated members as shown in FIG. 32. To prevent wedge 190 from being displaced by the action of engaging rod 176 wedge 190 is equipped with lugs 190a on the top and bottom which slide back and forth in slots in guide 192. Casing 193 of the engaging holder retains all of the units together in proper relation to the alignment guide 173 by being attached to the pivot 194. The partial wheel 181 of alignment guide 173 with its integral arm 195 rotates on pivot 194 which is attached by bolt 196 with washer retainer 197. This assembly is supported by member 72 of beam 64 and further braced by diagonal members 198.

The movement of arm 195 of the alignment guide 173 transmits the power to the positioning rods 168 and 169 through the flexible connectors 174 and 175 respectively. As shown in FIGS. 20, 21, 22, and 44 the connectors 174 and 175 are attached to the arm 195 through the pivot 200 and are run around the pulleys 201 and 202 supported by beam 202a and thence over the aligning pulleys 203 and 204 respectively. Flexible connector 174 is attached to the positioning rod 168 by means of the attachment 205 shown in FIGS. 26, 29, and 30 and continues on to the counterweight 183 after going over pulley 206 as shown in FIG. 4. In a similar manner connector 175 is attached to the positioning rod 169 by means of the attachment 207 and continues on to the counterweight 184 after going over pulley 208 as shown in FIGS. 4, 20 and 21. FIGS. 26 and 30 clearly show the design of attachments 205 and 207. They are secured to the positioning rods 168 and 169 respectively by means of metal rings 209 which are rigidly attached to the positioning rods 168 and 169.

and allow the rods 168 and 169 to rotate freely in the attachments 205 and 207.

A representative group of three alignment guides, three pairs of positioning rods, a pair of indexing rods, an alignment rod and an engagement rod are all shown in FIG. 44 to further illustrate how the various components work together. To review a typical operation a particular section of a particular aisle is cleared in a particular parking area and after clearing such section a particular carrier platform 160 is brought into position in alignment with such aisle either for receiving an incoming vehicle or for placing a vehicle to be unparked.

Before any of the alignment guides 173 are activated the indexing rods are positioned in such a manner as to bring all of the respective pairs of positioning rods 168 and 169 for subsequent appropriate lateral movement. This operation involves appropriate positioning of the lugs 170 as previously explained. Once this operation has been accomplished the engaging rods are next moved so as to bring the required alignment rod teeth into engagement with the appropriate alignment guide teeth. Once these teeth are properly set in engagement the next operation is that the piston 182 for the alignment rod 178 will move that appropriate distance required to actuate all of the engaged alignment guides so that all mating positioning rods will be caused to be moved as required and thereby effect movement of the appropriate platform carriers.

FIG. 50 illustrates in a greatly simplified form a control system covering electrical, hydraulic and pneumatic power sources as desired for a particular embodiment. Various interlocks, warning signals, safety switches and the like have not been shown and much of the circuitry illustrated would necessarily be duplicated depending on the number of bays, parking areas, parking levels, entrances, parking spaces etc. The invention thus provides a highly practical and versatile machine for the art.

What is claimed is:

1. In a multi-story parking machine for storing unattended free wheeled vehicles and the like, in combination:

- a. a basic machine structure providing a plurality of base level and other vertically spaced parking levels with each level having at least one parking area made of rectangular spaces defined by tracking for said vehicles, each space corresponding in width to the width of the widest and in length to the length of the longest vehicle to be stored, said spaces being arranged to form longitudinal and lateral rows which on the upper levels are aligned with those below, each said lateral row being designated as a bay and selected of said longitudinal rows being designated as aisles and which aisles are adapted to allow vehicular movement along the length thereof, said basic structure including at the base level a selected number of laterally spaced entranceways having tracking arranged to receive parked unattended free wheeled vehicles and to orient a selected number of streams of incoming and outgoing vehicular traffic in the direction of said aisles;
- b. a selected number of independently operable vehicle lifts one for each entranceway and located for

wardly of said entranceways, each said lift being adapted for individual selective actuation and when actuated and with a vehicle thereon being adapted to rise slightly from the base level, rotate 180° on its own axis to reverse the direction of the vehicle and to then position said vehicle to a selected one of said levels, each said lift having a vehicle lift carrier platform mounted thereon with tracking adapted when in its lowest position to align with a respective entranceway tracking whereby the vehicle may be rolled from such entranceway onto said lift carrier platform and when positioned at a selected parking level being adapted to align the lift carrier platform tracking with the tracking of a selected aisle on such selected level thereby providing for each parking level a corresponding number of lift serviced aisles alternating with non lift serviced longitudinal rows, said lifts having elevating portions adapted to rise from beneath, engage and lift said lift carrier platforms and said lift carrier platforms being physically detachable from the respective elevating portions of said lifts, said lifts further having fixed base level tracking on which said lift platforms are 25 adapted to rest when at said base level and having means to selectively move said lift carrier platforms laterally on such lift base level tracking whereby individual loaded and unloaded lift carrier platforms may be selectively positioned over 30 and between particular lift elevating portions to facilitate entry and discharge of vehicles from said machine;

c. a selected number of entranceway moving means, one being provided for each entranceway and 35 adapted for individual selective actuation and when so actuated adapted when an unattended free wheeled vehicle parked at such entranceway is to be parked in the machine to releasably grasp such vehicle at the entranceway and move it forwardly on its wheels on the respective entranceway tracking to the respective lift carrier platform tracking mating therewith and then being adapted to release the vehicle and move clear of such lift carrier platform, and when an unattended vehicle arrives on such lift carrier platform to be 40 discharged at the base level being adapted to releasably grasp such vehicle on the lift carrier platform and move it forwardly on its wheels from the tracking of such lift carrier platform back to the entranceway tracking mating therewith and then to release the vehicle and move clear thereof for removal by the operator thereof;

d. a plurality of rail mounted aisle moving means on each said parking level, one being provided for each respective lift serviced aisle on such level, each said aisle moving means being adapted for individual selective actuation and when so actuated being adapted upon arrival of a vehicle to be 45 stored to move as required to assume an operating position proximate said lift arrival position and at such operating position being adapted to releasably grasp the arriving vehicle and move such vehicle on its wheels from the tracking of the arriving lift carrier platform down the respective aisle tracking and stop such vehicle at a selected

aisle space position and there release and clear such vehicle and being adapted when a vehicle at such selected aisle space position is to be discharged to releasably grasp such vehicle and move it on its wheels from such selected aisle space position on the aisle tracking to a respective mating lift carrier platform tracking and there release and clear said vehicle lift carrier platform for repositioning to base level by the respective said lift;

e. laterally moveable vehicle storage platforms sufficient in number to fill each space except one empty space in each said bay, each group of storage platforms in each respective bay having tracking extending crosswise of the aisles intersecting therewith and means to shift each respective said storage platform laterally between a position in a respective lift serviced aisle and a position in a non lift serviced longitudinal row, when positioned in a lift serviced aisle each storage platform being adapted to receive a vehicle from or discharge a vehicle to tracking of such lift serviced aisle, in either position being adapted to store a vehicle thereon and being adapted by lateral movement of selected storage platforms in selected bays to remove a predetermined number of said platforms from the same selected lift serviced aisle whereby to clear the tracking of such aisle of said storage platforms for entry or discharge of a vehicle thereon; and

f. means to actuate said lifts, entranceway-lift moving means, aisle moving means and storage platforms in an appropriate coordinated sequence during storage and removal of vehicles from said main building structure.

2. A parking machine as claimed in claim 1 wherein said entrance-way-lift moving means comprises means to move the vehicle by engaging and asserting a force on a wheel of the vehicle in the desired direction of movement.

3. A parking machine as claimed in claim 1 wherein each said respective aisle moving means comprises moveable support means mounted for movement on rails above each respective lift serviced aisle, said support means having a pair of pivotal arm members adapted to releasably grasp front and rear surfaces of the vehicle and means to actuate said support means for movement on said rails and to actuate said arm members for grasping said vehicle whereby to effect said moving, stopping and clearing of said vehicle.

4. A parking machine as claimed in claim 1 wherein said parking levels above the base level include parking areas over said entranceways and which are arranged to be serviced by said lifts, aisle moving means and storage platforms.

5. A parking machine as claimed in claim 1 wherein said entranceway-lift moving means comprises an endless chain, moveable arm members mounted on said chain and having lowered and raised positions, a pair of spaced and rotatably mounted spindles on said arm members and adapted when said arm members are in a raised position to engage the left front wheel during parking and to engage the left rear wheel of the vehicle during unparking, piston means for raising and lowering said arm members, motor means for driving said

chain in one direction for parking and in an opposite direction for unparking and means for actuating said arm member piston means and motor means in an operational sequence.

6. A parking machine as claimed in claim 5 including a pair of guide bars mounted on a pivotal structure adjacent said entranceway-lift moving means and having piston means to actuate said pivotal structure whereby during parking one of said guide bars rises and guides the wheels on said vehicle and during unparking the other of said guide bars rises and guides said wheels. 5

7. A parking machine as claimed in claim 1 wherein each said aisle moving means includes a base frame mounted for movement on rails above a respective said lift serviced aisle, a pair of subframes mounted on opposite ends of said base frame and moveable back and forth thereon, and a pair of pivotal arm members one on each said sub-frame, and including means to actuate said subframes, pivotal arm members and base frame in an operational sequence to effect said releasable grasping, moving, stopping and releasing of said vehicle. 10 15 20

8. A parking machine as claimed in claim 1 wherein said means for laterally shifting said storage platforms includes for each bay a pair of axially and rotatably moveable positioning rods extending lengthwise of the bay below the platforms located therein, one of said pair being adapted in any lateral moving operation to move those and only those storage platforms required to be moved to the left and the other of said pair being adapted to move those and only those storage platforms required to be moved to the right, sets of longitudinally spaced selector lugs on each positioning rod adapted according to the rotative position of the positioning rod to provide selective engagement of selected platforms with selected lugs of selected positioning rods, lug connector means mounted below each respective said platform and adapted to engage and be disengaged from said lugs to effect said engagement, a pair of indexing rods extending lengthwise of each said parking area one of said indexing rods being adapted to rotate to a selected rotative position one member in each pair of positioning rods and the other of said indexing rods being adapted to rotate the other member in each pair of positioning rods to a selected rotative position, and positioning rod moving means effective following operation of said indexing rods to selectively move certain of said pairs of positioning rods in certain of said bays to effect said aisle clearing. 25 30 35 40 45 50

9. The method of machine storing vehicles in a multi-level structure having on each level spaces aligned in longitudinal and lateral rows, said lateral rows being designated as bays and certain of the longitudinal rows being designated for storage only and other longitudinal rows being designated as aisles for storage as well as movement along the length thereof, comprising the steps of:

- a. at a base level directing the incoming vehicles into laterally spaced plural streams oriented in the direction of the aisles;
- b. bringing each individual incoming vehicle to a halt in its respective stream and in an unattended entranceway position on wheel guide tracking and with the vehicle free to roll on the wheels thereof;
- c. mechanically rolling each respective incoming vehicle forwardly on said guide tracking and onto

a respective vehicle lift having guide tracking mating with the respective entranceway guide tracking and capable of rotating the vehicle and positioning it at any said level to mate with a respective aisle on such level;

- d. rotating the vehicle 180 degrees on the lift followed by positioning to the selected level and at a position mating with a respective aisle having guide tracking on such level;
- e. mechanically rolling said vehicle from said lift down said respective aisle tracking to a selected space and at said space stopping said vehicle on a storage carrier having mating guide tracking and capable of moving laterally from the selected space in said respective aisle to a space in an adjacent said longitudinal row;
- f. maintaining said vehicle and each successive said vehicle stored on such a said carrier and while always reserving one empty space in each said bay utilizing said lateral shift capability to shift said carriers laterally between said longitudinal rows and aisles to open any said aisle at any time as required and storing said carriers with vehicles thereon in selected ones of said spaces except in said reserved spaces;
- g. discharging said vehicles from said structure by utilizing said lateral shift capability and said reserve spaces to open the tracking of any aisle at any time as required to allow discharge of vehicles on the tracking at such opened aisle;
- h. mechanically rolling selected vehicles to be discharged down a respective said opened aisle tracking and onto a respective said lift tracking mating therewith and brought to the respective level having such aisle;
- i. positioning the vehicle to base level by means of said lift;
- j. mechanically rolling the vehicle from said lift tracking back to the respective mating said entranceway tracking position for removal by the operator thereof; and
- k. including the step during handling of the vehicle of mechanically rolling the vehicle onto a laterally moveable lift platform having said lift guide tracking and which platform is detachable from but is adapted to be lifted by a selected said lift and while on such platform lift guide tracking shifting said lift platform and the vehicle thereon laterally clear of the lift whereby to free such lift for receiving another such lift platform.

10. The method of claim 9 wherein said step of 55 mechanically rolling each vehicle onto a respective lift comprises mechanically rasping the left front wheel of the vehicle between a pair of rotatable rollers and moving the rollers in unison to effect rolling of the vehicle.

11. The method of claim 9 wherein said step of 60 mechanically rolling the vehicle along said respective aisle comprises mechanically clamping the vehicle between a pair of pivotal arms mounted on a base frame adapted to move on rails down the respective aisle above the vehicle and after such clamping moving the base frame down said respective aisle, then stopping said base frame and releasing said pivotal arms from the vehicle.

12. The method of claim 9 wherein during parking or unparking of a vehicle in a selected space said lateral shift capability of said storage carriers is used by laterally shifting those carriers necessary to clear the respective aisle prior to any required lateral shifting of the particular carrier on which the vehicle is to be parked or from which it is to be unparked.

13. In a parking machine for storing unattended free wheeled vehicles and the like, in combination:

a. a basic machine structure providing at least one parking level having at least one parking area made up of rectangular spaces defined by tracking for said vehicles, each space corresponding in width to the width of the widest and in length to the length of the longest vehicle to be stored, said spaces being arranged to form longitudinal and lateral rows, each said lateral row being designated as a bay and selected of said longitudinal rows being designated as aisles and which aisles are adapted to allow vehicular movement along the length thereof;

b. a vehicular aisle mover located in each aisle of each said parking level, each said aisle mover being adapted for individual selective actuation and when so actuated being adapted upon arrival at the respective aisle of a vehicle to be stored to move from its then position to an operating position proximate said vehicle arrival position and at such operating position being adapted to releasably grasp the arriving vehicle and move such vehicle on its wheels from the arrival position down the respective aisle tracking and stop such vehicle at a selected aisle space position and there release and clear such vehicle and being adapted when a vehicle at such selected aisle space position is to be discharged to move from its then position to a position proximate said aisle space position and there releasably grasp such vehicle and move it on its wheels from such selected aisle space position on the aisle tracking to a respective discharge position and there release and clear said vehicle, each said aisle mover including a base frame and rails, said base frame being mounted for movement on the rails above the respective said aisle which said aisle mover services, a pair of sub-frames mounted on opposite ends of said base frame and moveable back and forth thereon, and a pair of pivotal arm members one on each said sub-frame, and including means to actuate said sub-frames, pivotal arm members and base frame in an operational sequence to effect said releasable grasping, moving, stopping and releasing of said vehicle;

c. laterally moveable vehicle storage platforms sufficient in number to fill each space except one empty space in each said bay, each group of storage platforms in each respective bay having tracking extending crosswise of the aisles intersecting therewith and means to shift each respective said storage platform laterally on such crosswise tracking between a position in a respective aisle and a position in a longitudinal row not an aisle, when positioned in an aisle each storage platform being positioned above the tracking of such aisle and adapted to receive a vehicle from or

discharge a vehicle to tracking of such aisle, in either position each said storage platform being adapted to track and store a vehicle thereon and being adapted by lateral movement of selected storage platforms in selected bays to remove a predetermined number of said platforms from the same selected aisle whereby to clear the tracking of such aisle of said storage platforms for entry or discharge of a vehicle thereon; and

10 d. means to actuate said aisle movers and storage platforms in an appropriate coordinated sequence during storage and removal of vehicles from said basic structure.

14. A parking machine as claimed in claim 13 wherein said means for laterally shifting said storage platforms includes for each bay a pair of axially and rotatably moveable positioning rods extending lengthwise of the bay below the platforms located therein, one of said pair being adapted in any lateral moving operation to move those and only those storage platforms required to be moved to the left and the other of said pair being adapted to move those and only those storage platforms required to be moved to the right, sets of longitudinally spaced selector lugs on each positioning rod adapted according to the rotative position of the positioning rod to provide selective engagement of selected platforms with selected lugs of selected positioning rods, lug connector means mounted below each respective said platform and adapted to engage and be disengaged from said lugs to effect said engagement, a pair of indexing rods extending lengthwise of each said parking area one of said indexing rods being adapted to rotate to a selected rotative position one member in each pair of positioning rods and the other of said indexing rods being adapted to rotate the other member in each pair of positioning rods to another selected rotative position, and positioning rod moving means effective following operation of said indexing rods to selectively move certain of said pairs of positioning rods in certain of said bays to effect said aisle clearing.

15. A parking machine as claimed in claim 13 wherein said machine includes an entranceway and an entranceway mover having an endless chain, moveable arm members mounted on said chain and having lowered and raised positions, a pair of spaced and rotatably mounted spindles on said arm members and adapted when said arm members are in a raised position to engage the left front wheel during parking and to engage the left rear wheel of the vehicle during unparking, piston means for raising and lowering said arm members, motor means for driving said chain in one direction for parking and in an opposite direction for unparking and means for actuating said arm member piston means and motor means in an operational sequence.

16. A parking machine as claimed in claim 15 including a pair of guide bars mounted on a pivotal structure adjacent said entranceway mover and having piston means to actuate said pivotal structure whereby during parking one of said guide bars rises and guides the wheels on said vehicle and during unparking the other of said guide bars rises and guides said wheels.

17. In a multi-story parking machine for storing unattended free wheeled vehicles and the like, in combination:

- a. a basic machine structure providing a plurality of base level and other vertically spaced parking levels with each level having at least one parking area made of rectangular spaces defined by tracking for said vehicles, each space corresponding in width to the width of the widest and in length to the length of the longest vehicle to be stored, said spaces being arranged to form adjacent longitudinal and adjacent lateral rows which on the upper levels are aligned with those below, each 5 said lateral row being designated as a bay and selected of said longitudinal rows being designated as aisles and which aisles are adapted to allow vehicular movement along the length thereof, said basic structure including at the base level a selected number of laterally spaced entranceway having tracking arranged to receive parked unattended free wheeled vehicles and to orient a selected number of streams of incoming and outgoing 10 vehicular traffic in the direction of said aisles;
- b. a selected number of independently operable vehicle lifts one for each entranceway and located forwardly of said entranceways, each said lift being 15 adapted for individual selective actuation and when actuated and with a vehicle thereon being adapted to rise and to position said vehicle to a selected one of said levels, each said lift having a vehicle lift carrier platform mounted thereon with tracking adapted when in its lowest position to align with a respective entranceway tracking whereby the vehicle may be rolled from such entranceway onto said lift carrier platform and when positioned at a selected parking level being 20 adapted to align the lift carrier platform tracking with the tracking of a selected aisle on such selected level thereby providing for each parking level a corresponding number of lift serviced aisles 25 alternating with non-lift serviced longitudinal rows;
- c. a selected number of base level located entranceway moving means, one being provided for each entranceway and adapted for individual selective actuation and when so actuated adapted when an unattended free wheeled vehicle parked at such entranceway is to be parked in the machine to 30 releasably grasp such vehicle at the entranceway and move it forwardly on its wheels on the respective entranceway tracking to the respective lift carrier platform tracking mating therewith and then being adapted to release the vehicle and move clear of such lift carrier platform, and when an unattended vehicle arrives on such lift carrier platform to be discharged at the base level being 35 adapted to releasably grasp such vehicle on the lift carrier platform and move it forwardly on its wheels from the tracking of such lift carrier platform back to the entranceway tracking mating therewith and then to release the vehicle and move 40 clear thereof for removal by the operator thereof;
- d. a selected number of aisle moving means located on each said parking level, one being provided for each respective lift serviced aisle on such level, each aisle moving means being mounted for movement on rail means extending parallel to said lift serviced aisle and adjacent the path of the respec- 45

- tive lift serviced thereby, each said aisle moving means being adapted for individual selective actuation and when so actuated being adapted in timed relation to the arrival of a vehicle to be stored to move as required to assume an operating position on its respective said rail means proximate said lift arrival position and at such operating position being adapted to releasably grasp the arriving vehicle and move such vehicle on its wheels from the tracking of the arriving lift carrier platform down the respective aisle tracking and stop such vehicle at a selected aisle space position and there release and clear such vehicle forwardly, rearwardly and laterally and being adapted when a vehicle at such selected aisle space position is to be discharged to move on its said respective rail means to assume a position proximate said aisle space position and to releasably grasp such vehicle and move it on its wheels from such selected aisle space position on the aisle tracking to and in timed relation with the arrival of a respective mating lift carrier platform tracking and there release and clear said vehicle and its carrier platform for repositioning to base level by the respective said lift;
- e. laterally moveable vehicle storage platforms sufficient in number to fill each space except one empty space in each said bay, each group of storage platforms in each respective bay having supporting tracking extending crosswise of the aisles intersecting therewith and means to shift each respective said storage platform laterally between a position in a respective lift serviced aisle and an immediately adjacent position in a non-lift serviced longitudinal row, when positioned in a lift serviced aisle each storage platform being adapted to receive a vehicle from or discharge a vehicle to tracking of such lift serviced aisle, in either position being adapted to store a vehicle thereon and being adapted by lateral movement of selected storage platforms in selected bays to remove a predetermined number of said platforms from the same selected lift serviced aisle whereby to clear the tracking of such aisle of said storage platforms for entry or discharge of a vehicle thereon;
- f. elevating portions for said lifts adapted to rise from beneath, engage and lift said carrier platforms and said lift carrier platforms being each physically detachable from the respective elevating portions of said lifts and said lifts further including fixed base level tracking on which such lift carrier platforms are adapted to rest when at base level and means to selectively move said lift carrier platforms laterally on such base level lift tracking whereby individual loaded and unloaded lift carrier platforms may be selectively positioned over and between particular lift elevating portions to facilitate entry and discharge of vehicles from said machine; and
- g. control means to actuate said lifts, lift elevating portions, entranceway-lift moving means, aisle moving means and storage platforms lift means in an appropriate coordinated time sequence during storage and removal of vehicles from said main building structure.

18. A parking machine as claimed in claim 17 wherein each said respective aisle moving means comprises moveable support means mounted for movement on said rail means, said support means having a pair of pivotal arm members adapted to releasably grasp front and rear surfaces of the vehicle and means to actuate said support means for movement on said rails and to actuate said arm members for grasping said vehicle whereby to effect said moving, stopping and clearing of said vehicle.

19. A parking machine as claimed in claim 17 wherein said entranceway-lift moving means comprises an endless chain, moveable arm members mounted on said chain and having lowered and raised positions, a pair of spaced and rotatably mounted spindles on said arm members and adapted when said arm members are in a raised position to engage a front wheel during parking and to engage a rear wheel of the vehicle during un-parking, operator means for raising and lowering said arm members, motor means for driving said chain in one direction for parking and in an opposite direction for un-parking and means for actuating said arm member operator means and motor means in an operational sequence.

20. A parking machine as claimed in claim 17 including a pair of guide bars mounted on a pivotal structure adjacent said entranceway-lift moving means and having actuator means to actuate said pivotal structure whereby during parking one of said guide bars rises and guides the wheels on said vehicle and during unparking the other of said guide bars rises and guides said wheels.

21. A parking machine as claimed in claim 17 wherein each said aisle moving means includes a base frame mounted for movement on said rail means adjacent a respective said lift serviced aisle, a pair of sub-frames mounted on opposite ends of said base frame and moveable back and forth thereon, and a pair of pivotal arm members one on each said sub-frame, and including means to actuate said sub-frames, pivotal arm members and base frame in an operational sequence to effect said releasable grasping, moving, stopping and releasing of said vehicle.

22. A parking machine as claimed in claim 17 wherein said means for laterally shifting said storage platforms includes for each bay a pair of axially and rotatably moveable positioning rods extending lengthwise of the bay below the platforms located therein, one of said pair being adapted in any lateral moving operation to move those and only those storage platforms required to be moved to the left and the other of said pair being adapted to move those and only those storage platforms required to be moved to the right, sets of longitudinally spaced selector lugs on each positioning rod adapted according to the rotative position of the positioning rod to provide selective engagement of selected platforms with selected lugs of selected positioning rods, lug connector means mounted below each respective said platform and adapted to engage and be disengaged from said lugs to effect said engagement, a pair of indexing rods extending lengthwise of each said parking area one of said indexing rods being adapted to rotate to a selected rotative position one member in each pair of positioning rods and the other of said indexing rods being adapted

to rotate the other member in each pair of positioning rods to a selected rotative position, and positioning rod moving means effective following operation of said indexing rods to selectively move certain of said pairs of positioning rods in certain of said bays to effect said aisle clearing.

23. In a multi-story parking machine for storing unattended free wheeled vehicles and the like, in combination:

- 10 a. a basic machine structure providing a plurality of base level and other vertically spaced parking levels with each level having at least one parking area made of rectangular spaces defined by tracking for said vehicles, each space corresponding in width to the width of the widest and in length to the length of the longest vehicle to be stored, said spaces being arranged to form adjacent longitudinal and adjacent lateral rows which on the upper levels are aligned with those below, each said lateral row being designated as a bay and selected of said longitudinal rows being designated as aisles and which aisles are provided with means to support vehicles for movement along the length thereof, said basic structure including at the base level a selected number of laterally spaced entranceways having tracking arranged to receive parked unattended free wheeled vehicles and to orient a selected number of streams of incoming and outgoing vehicular traffic in the direction of said aisles;
- 15 b. a selected number of independently operable vehicle lifts one for each entranceway and located forwardly of said entranceways, each said lift being adapted for individual selective actuation and when actuated and with a vehicle thereon being adapted to rise and to position said vehicle to a selected one of said levels, each said lift having a vehicle lift carrier platform mounted thereon with tracking adapted when in its lowest position to align with a respective entranceway tracking whereby the vehicle may be rolled from such entranceway onto said lift carrier platform and when positioned at a selected parking level being adapted to align the lift carrier platform tracking with the tracking of a selected aisle on such selected level thereby providing for each parking level a corresponding number of lift serviced aisles alternating with non-lift serviced longitudinal rows;
- 20 c. a selected number of base level located entranceway moving means, one being provided for each entranceway and adapted for individual selective actuation and when so actuated adapted when an unattended free wheeled vehicle parked at such entranceway is to be parked in the machine to releasably grasp such vehicle at the entranceway and move it forwardly on its wheels on the respective entranceway tracking to the respective lift carrier platform tracking mating therewith and then being adapted to release the vehicle and move clear of such lift carrier platform, and when an unattended vehicle arrives on such lift carrier platform to be discharged at the base level being adapted to releasably grasp such vehicle on the lift carrier platform and move it forwardly on its

wheels from the tracking of such lift carrier platform back to the entranceway tracking mating therewith and then to release the vehicle and move clear thereof for removal by the operator thereof;

d. a selected number of aisle moving means located 5 on each said parking level, one being provided for each respective lift serviced aisle on such level, each aisle moving means being mounted for movement on rail means extending parallel to said lift serviced aisle and extending horizontally across 10 and adjacent each side of the vertical path of the respective lift serviced thereby, each said aisle moving means being adapted for individual selective actuation and when so actuated being adapted in timed relation to the arrival of a vehicle to be 15 stored to move as required to assume an operating position on its respective said rail means proximate and, above said lift arrival position and at a vertical position above said vehicle support means and at such operating position being adapted to 20 releasably grasp the arriving vehicle and move such vehicle on its wheels from the tracking of the arriving lift carrier platform down the respective aisle tracking and stop such vehicle at a selected aisle space position and there release and clear 25 such vehicle forwardly, rearwardly and laterally and being adapted when a vehicle at such selected aisle space position is to be discharged to move on its said respective rail means to assume a position proximate said aisle space position and to 30 releasably grasp such vehicle and move it on its wheels from such selected aisle space position on

the aisle tracking to and in timed relation with the arrival of a respective mating lift carrier platform tracking and there release and clear said vehicle and its carrier platform for repositioning to base level by the respective said lift;

e. laterally moveable vehicle storage platforms sufficient in number to fill each space except one empty space in each said bay, each group of storage platforms in each respective bay having supporting tracking extending crosswise of the aisles intersecting therewith and means to shift each respective said storage platform laterally between a position in a respective lift serviced aisle and an immediately adjacent position in a non-lift serviced longitudinal row, when positioned in a lift serviced aisle each storage platform being adapted to receive a vehicle from or discharge a vehicle to tracking of such lift serviced aisle, in either position being adapted to store a vehicle thereon and being adapted by lateral movement of selected storage platforms in selected bays to remove a predetermined number of said platforms from the same selected lift serviced aisle whereby to clear the tracking of such aisle of said storage platforms for entry or discharge of a vehicle thereon; and

f. control means to actuate said lifts, entranceway-lift moving means, aisle moving means and storage platforms lift means in an appropriate coordinated time sequence during storage and removal of vehicles from said main building structure.
